ROOFING OR SURFACING MATERIAL

Sidney Lanier Eason, Charleston, S. C.

Application July 16, 1940, Serial No. 345,765

3 Claims. (Cl. 108—7)

This invention relates to roll roofing, and is an improvement upon the structures illustrated in my prior Patents Nos. 2,003,503 and 2,160,845, and my copending application Serial No. 276,789, in respect to the manner of obtaining a fabric-to-fabric seal at the joining or lapping areas of related courses of roofing.

In my aforesaid inventions I taught fabric-to-fabric sealing relationship by the use of adhesively coated surfaces which were responsive to a hot iron or its equivalent, usually followed by application of an after cement or coating composition to supplement the fabric-to-fabric seal thus developed.

In order to save labor in field application, as well as to avoid complications in the manufacture and shipment of roll roofing by supplying a quantity of cement in liquid or plastic form, I develop the fabric-to-fabric seal in my present invention by means of a separate sealing strip having cohesive affinity for the pre-attached strip, flap or flaps with which my roll roofing is factory-equipped. Such sealing strip makes after-cementing unnecessary, thus effecting a worthwhile saving in labor and materials, while however, providing ample protection at the joint.

In the accompanying drawing:

Fig. 1 shows a typical joint at the overlapping edges of two related courses of roofing material each of which is provided at one edge with a foldable fabric flap strip, there being between the attaching area of one flap strip and the overfolded flap area of the other flap strip an in-between fabric sealing strip having cohesive affinity for said flaps, and said sealing strip being overfolded upon itself with the flaps to provide double protection for the nail heads and having fabric-to-fabric seal with said flap strips.

Fig. 2 is a section showing another variant in which one roofing course only is equipped with a fabric selvage strip, which strip and the nail heads are covered by a sealing strip in accordance with my invention.

Fig. 3 is a section showing still another variant in which one roofing course is provided with a foldable fabric flap strip, the flap area of which is of greater length than the flap area of either of the flap strips shown in Fig. 1, the other roofing course being provided with a fabric selvage strip, and there being an in-between fabric sealing strip covering the nail heads and covered by the overfolded flap, said in-between sealing strip having fabric-to-fabric seal with the selvage strip and with the flap strip.

Fig. 4 is a section showing still another variant

in which both roofing courses are equipped with foldable fabric flap strips and these strips are themselves coated in certain areas with a substance having cohesive affinity with the material of the flap strips, and

Fig. 5 is a section showing a still further variant in which both roofing courses are provided at the upper and lower faces, respectively, of their overlapping edges with fabric selvage strips having cohesive affinity for one another.

As disclosed generally in my aforesaid patents and patent applications, my present invention involves mastic saturated or composition or coated roll roofing of conventional type which is equipped at the factory with fabric or equivalent flap strips at one or both longitudinal edges, or with fixed fabric selvage strips, or with a foldable fabric flap strip at one longitudinal edge and a fixed fabric selvage strip at its opposite longitudinal edge.

In all figures of the drawing, the boarding of a roof is indicated at 10 and is covered by related courses of composition roofing material 11 and 12 which are overlapped as shown at their joining edges and nailed as at 13 to the roofing. The joint thus produced is covered and protected by a fabric-to-fabric seal developed in any of the several manners illustrated in Figs. 1 to 5 inclusive.

30 In Fig. 1 each roofing course has cemented or otherwise attached to one marginal edge thereof a foldable fabric flap strip. The flap strip of the course 11 comprises an attaching portion 14 and an overfolded flap portion 15. The flap strip of the course 12 comprises an attaching portion 16 and an overfolded flap portion 17.

Between the flap strips before the same are overfolded is placed a fabric sealing strip 18 which carries a substance having cohesive affinity for the material of the flap strips. When the flap portions 15 and 17 are overfolded upon one another, the sealing strip is likewise overfolded upon itself to provide double protection for the nail heads. Thus, the overfolded sealing strip has fabric-to-fabric seal with the attaching portion 16 of the flap strip 16—17 and with the flap portion 15 of the flap strip 14—15, and is completely enclosed within said overfolded flap strips.

40 In Fig. 2, the fabric-to-fabric seal is provided by a fabric selvage strip 20 applied to the overlapping marginal edge of the roofing course 11 and a sealing strip 21 preferably coextensive therewith and carrying a substance having co-

hesive affinity for the material of the selvage strip.

In the joint of Fig. 3 the roofing course 11 is provided at its overlapping marginal edge with a foldable fabric flap strip 22—23—24. The portion 22 is the attaching portion, the portion 23 is the overfolded flap portion, and the portion 24 is an extension of said overfolded flap portion 23. The related roofing course 12 is provided with a fabric selvage strip 25 corresponding generally 10 to the selvage strip 20 of Fig. 2. Laid over the flap strip before it is overfolded upon itself is a fabric sealing strip 26 corresponding to the sealing strip 18 of Fig. 1, but extending as a single layer when the joint is made. The sealing strip 26 covers the nail heads but is covered by the portions 23—24 of the flap strip, being in fabric-to-fabric sealing relationship with all portions of the flap strip, and also being sealed down upon the selvage strip 25 and covered by the extended portion 24 of the flap strip.

In the joint of Fig. 4, both roofing courses 11 and 12 are provided with foldable fabric flap strips 27—28 and 29—30, respectively, the portions 27 and 29 being attaching portions and the portions 28 and 30 being flap portions. The attaching portions 27 and 29 are attached to the respective courses of roofing material in any suitable manner. If adhesively attached, they are attached with an adhesive different from the adhesive coating which is applied to other areas of the flap strips. The exposed faces of said attaching portions 27 and 29, as well as the flap portions 28 and 30 are coated with a substance having cohesive affinity for each other so that when the flaps are folded into overlapping relationship these coated surfaces adhere to each other. The aforesaid coating substance is one, however, which has the property of not adhering to other surfaces so that the unfolded flaps (or selvage edge strips, if selvage strips are substituted for the flap strips) will not adhere to the roofing when shipped in the roll. As an example of such substance I may use latex of the kind now on the market sold under the name "Vultex," or rubber composition or similar as used in so-called friction tapes. Thus in this form of my invention I obtain a fabric-to-fabric seal without the necessity of using a separate sealing strip as in Figs. 1 to 3 inclusive.

This is also true of the joint illustrated in Fig. 5. In Fig. 5 the upper and lower surfaces of the respective roofing courses 11 and 12 are provided at their overlapping edges with fabric selvage

strips 31 and 32. These strips are pretreated with a substance having cohesive affinity for each other and the joint is made by simply pressing the strips into pressure contact with each other.

In all forms where a sealing strip is used such strip will be furnished separately of the roll of roofing material but on account of its relatively small size can be placed within the roll as regularly packaged.

The term "fabric" as used herein in connection with either the flap strips, the selvage strips, or the sealing strips is used in its broadest sense, and is intended to include any materials having the general properties of fabric.

What I therefore claim and desire to secure by Letters Patent is:

1. In roofing, adjacent courses of roofing material, a fabric strip extending along the adjacent edge of each course for fabric-to-fabric seal when the adjacent edges of said courses are brought into joint-forming relationship with each other, and a coating substance applied to at least one of said strips having cohesive affinity for said strips, but being non-adherent to said courses of roofing material.

2. In roofing, adjacent courses of roofing material, a foldable fabric flap strip extending along the adjacent edge of each course for fabric-to-fabric seal with each other when the adjacent edges of said courses are brought into joint-forming relationship, and a fabric sealing strip interposed between said flap strips and confined thereby when the flap portions of said flap strips are overfolded upon one another, said sealing strip being coated with a substance having cohesive affinity for said flap strips but being non-adherent to said courses of roofing material.

3. In roofing, adjacent courses of roofing material, a foldable fabric flap strip extending along the longitudinal edge of one roofing course and a fixed fabric selvage strip extending along the longitudinal edge of the other roofing course for fabric-to-fabric seal with said flap strip when the adjacent edges of said courses are brought into joint-forming relationship, and a fabric sealing strip interposed between said flap and selvage strips and confined thereby when the flap portion of said flap strip is overfolded upon said selvage strip, said sealing strip being coated with a substance having cohesive affinity for said flap and selvage strips but being non-adherent to said courses of roofing material.

SIDNEY LANIER EASON.
